STANLEY LEONARD CAHN, OF BALTIMORE, MARYLAND, ASSIGNOR TO PUBLICITY SERVICE, INC., OF BALTIMORE, MARYLAND, A CORPORATION OF MARYLAND

DISPLAY CARD

Application filed May 28, 1931. Serial No. 540,782.

The object of this invention is to provide a display card or folder in which an image or device is automatically drawn across the face of the card as the card is opened and closed. 5 The invention consists of a card transversely creased so as to be capable of being folded, one of the folds having permanently attached thereto on one side of the line of the crease an image or object, such image or object being movably attached to the other fold 10 on the opposite side of the line of the crease, so that the image, when the card is folded, is moved to one side of the line of crease and when the card is unfolded the image will be 15 caused to travel or move across the face of the card, so as to represent an image or object in motion, as I will proceed now to more fully explain and finally claim.

In the accompanying drawings illustrating the invention, in the several figures of which like parts are similarly designated, Figure 1 is an inside plan view of the device in open position. Fig. 2 is a perspective view showing the image or object in motion as the 25 card is moved from a folded condition into an open condition.

The device embodies a rectangular or other shape card, composed of the folds or leaves 1 and 2 separated by a crease 3 extending transversely of the card and forming a line of fold between the two folds or leaves 1 and 2, whereby said folds or leaves may be opened out, as shown in Fig. 1, into a perfectly flat condition and may be moved toward each 35 other, as indicated in Fig. 2, to present the card in a folded condition where the two folds or leaves may be brought together one upon the other.

The folds or leaves may be provided with 40 any desired illustrations or advertising matter, as indicated in Fig. 1, where a traffic officer is shown governing the movements of an automobile and a tricycle rider.

The traffic officer and the automobile are 45 fixed, while the tricycle is so mounted as to actually move across the face of the card or folder as the leaves of the card are moved back and forth on their crease or line of fold 3. As shown, there is a carrier 4 permanently fixed at 5 to one of the folds or

leaves and provided with a crease or hinge 6 and this carrier extends from this fixed portion across the line of fold 3 and is provided with a transverse crosshead 7, the ends of which extend through a pair of parallel longitudinal slits 8 and 9 on the fold or leaf 2. The material 10 between the slits 8 and 9 remains as a permanent part of the leaf 2, so that when the folds or leaves are moved toward and from each other, the carrier will 60 be caused to move back and forth across the face of the card or folder. 55

This material 10 serves as a base for the movement of the crosshead, and with the projecting ends of the crosshead overlying the 65 part 10 and adjacent portion of the fold or leaf 2 so as to retain the moving object in connection with the card.

This carrier may have mounted upon it, or as a part of it, the representation of any 70 device which is ordinarily a motion device, and I have herein shown the representation of a tricycle on which a child is mounted. Any other moving object may be used as a part of or a fixture upon the carrier and the 75 legends on the card may be such as to be appropriate to the moving article.

As already indicated, when the card is opened up flat, as in Fig. 1, all the parts are stationary, but when the folds or leaves of the card are moved from the flat position into a folded position or any position between the flat and the completely folded position or from the folded position into the flat position, the moving object will be caused 80 to traverse the face of the card from one side to the other. The attached part of the carrier 5 forms a sort of pivot for the carrier and said carrier is therefore capable of movement from such pivoted part across the face 85 of the card, as indicated in part in Fig. 2.

Fig. 2 shows the folded card as well as the movable image in outline, and with the image moved from the position shown in Fig. 1 to a position to the right hand side of that position, and away from the line of fold or crease 3. 90

I am aware that it is not broadly new to provide a display folder or card with an image representing motion and actually hav- 100

ing motion as the card or folder is opened and closed.

Variations in the details of construction are permissible within the principle of the 5 invention and the claims following.

What I claim is:—

1. A display card, comprising foldable leaves containing any suitable fixed display matter and an image mounted on a carrier, 10 which carrier is pivotally connected to one of the leaves and extends thence crosswise of the other leaf and movably connected with said other leaf by means of parallel slits in said other leaf and a crosshead on 15 one end of the carrier in sliding engagement with said slits, so that by folding and unfolding the leaves, said object so mounted will be caused to move transversely across the leaves.
2. A display card, creased midway between its ends and so providing connected folds or leaves, and an image carrier pivoted to one 20 of the folds or leaves to one side of the line of crease and extending thence across the line 25 of crease over the other fold or leaf, said second mentioned fold or leaf having parallel slits extending longitudinally of the carrier and said carrier having a crosshead fitted in said slits and movable therein across the 30 face of the card as the card is opened and closed.
3. A display card, creased midway between its ends and providing connected folds or leaves, and an image carrier pivoted to one 35 of the folds or leaves to one side of the line of crease and extending thence across the line of crease over the other fold or leaf, said second mentioned fold or leaf having a pair of parallel slits extending lengthwise 40 relatively to the image carrier and said carrier having a cross head fitted in said slits and movable therein across the face of the card as the card is opened and closed, the material of the card between the slits serving 45 as a base for the movement of the moving image.

In testimony whereof I have hereunto set my hand this 25th day of May, A. D. 1931.

STANLEY LEONARD CAHN.
